UNITED STATES PATENT OFFICE.

FRANK O. ACKERS, OF COLUMBUS, OHIO, ASSIGNOR TO THE SAFETY WIRE GAS GLOBE COMPANY, OF COLUMBUS, OHIO, A CORPORATION OF OHIO.

METHOD OF MANUFACTURING WIRE GLOBES.

1,321,410.

Specification of Letters Patent.

Patented Nov. 11, 1919.

Application filed June 12, 1918. Serial No. 239,667.

To all whom it may concern:

Be it known that I, FRANK O. ACKERS, a citizen of the United States, residing at Columbus, in the county of Franklin and 5 State of Ohio, have invented certain new and useful Improvements in Methods of Manufacturing Wire Globes, of which the following is a specification.

This invention relates to an improved 10 method of fabricating and producing foamed articles of manufacture, and has particular reference to an improved method of manufacturing and treating wire netting to produce a substantial and light radiating protective globe or covering for use 15 in connection with incandescent mantles, whereby a globe of superior strength and durability will be provided, combining lightness in weight and excellent light diffusing characteristics.

One of the main objects of the invention resides in an improved method of producing wire mesh globes, which consists substantially in subjecting a body of wire netting to a shaping process, in order to produce a globe of proper contour, and in applying an enamel coating to the globe so as to impart a light diffusing color thereto, and at the same time to form the coating 20 from such ingredients that it will congeal or solder around the joints formed by the intersecting wire strands, so that the latter will be securely bonded together and a substantial and rigid structure produced.

For a further disclosure of the invention reference is to be had to the following description and to the accompanying drawing, forming a part of this specification, and in which drawing similar characters of reference denote like parts throughout its several views.

In the drawing:

Figure 1 is a blank view of a sheet of wire netting from which the globe embodying the features of this invention is formed,

Fig. 2 discloses the manner of subjecting the netting to a die to form its globular contour,

Fig. 3 is a view of the completed globe,

Fig. 4 is an enlarged fragmentary sectional view, disclosing the joint formed by an intersecting pair of wire strands, and illustrating the application and effect of the enameling and solidifying coating applied thereto.

With regard to the details of carrying out my improved method, a sheet 1 of a suitable size of wire netting, shown in Fig. 1, is submitted to the action of a rotatable die structure 2 which, as will be observed 60 upon reference to Fig. 2, shapes the sheet 1 to assume the globular or other desired contour shown. Subsequently to the shaping action of the die structure, the protruding ends 3 of the globe are severed to round 65 off or finish the edges of the globe, so that an even circular edge will be provided. To this edge there is suitably connected an annulus 4, in order to reinforce said edge and to permit the globe to be conveniently connected with any suitable form of mounting 70 (not shown) for purposes of application and practical usage in connection with a lamp structure.

Coming now to a more important phase 75 of the invention, I provide a method of treating this globe, subsequent to the shaping process, to increase its durability, rigidity and general strength, and at the same time to color or coat the same in 80 order to enhance its light diffusing properties. To this end, I preferably apply a paint, enamel or any other suitable mobile coating to the strands of the globe. This is preferably accomplished by dipping a 85 shaped globe into a coating having the general properties and consistency of paint, and then through the use of compressed air the surplus coating is pneumatically blown off of the globe leaving a coat of required 90 thickness thereon. This coat is permitted to dry and harden on the wire strands and annulus 4 in any suitable manner, a bake oven being capable of being advantageously 95 employed to hasten this drying process.

By thus treating the wire strands of the globe the following results obtain among others; First, the joints formed by the intersecting wire strands are firmly, rigidly and securely united, this overcomes the 100 flexibility of the globe, resulting from the shaping process, and renders the same substantial, stiff and capable of withstanding such stresses and strains as are incident to normal use without losing its desired or 105 proper contour. At this juncture, it is advisable to state that when the sheet of wire netting 1 is subjected to the shaping process, the strands of wire, which were firmly united during the initial process of manu- 110

facturing and electro-plating the netting 1, are bent or distorted from their original positions to produce the globular contour shown, thus breaking the original joints and 5 rendering the body decidedly plastic and responsive to shape altering pressures. However, through the application of the coating described the intersecting strands are again bonded, in the manner suggested 10 by Fig. 4, to reestablish a firm, solid and substantial union therebetween, and to thereby restore and enhance the general 15 rigidity of the globe structure. And, secondly, the coating set forth contains a suitable pigment which preferably colors 20 the globe to produce a white enamel effect, whereby when the globe is in use the strands comprising the same permit light to be diffused and protected in substantially the same manner as and without the objections of a frosted glass globe.

From the foregoing description it will be

apparent to those versed in the art that there is provided an improved method of producing wire mesh globes, and one where- 25 in a globe is produced possessing excellent features of substantial construction, facility and economy in manufacture, capable of protecting an inclosed mantle from undue drafts, air currents or other damaging and 30 disturbing influences and which will in no way interfere with or retard light diffusion.

I claim:

The improved method of producing wire mesh globes consisting in shaping a body of 35 wire netting to assume a globular contour, and in subsequently applying a bonding coating of light diffusing properties to said netting to again unite the intersecting strands thereof which were dislocated dur- 40 ing the shaping process.

In testimony whereof I affix my signature.

FRANK O. ACKERS.
